PIANO BENCH

George W. Smith, Newburgh, N. Y.

Application April 19, 1938, Serial No. 202,963

4 Claims.

(Cl. 155—34)

The present invention relates to new and useful improvements in piano benches and has for its primary object to provide, in a manner as hereinafter set forth, a device of this character embodying a novel construction, combination and arrangement of parts through the medium of which a plurality of vertical adjustments may be expeditiously made.

Other objects of the invention are to provide an adjustable piano bench of the aforementioned character which will be comparatively simple in construction, strong, durable, highly efficient and reliable in use, compact, light in weight, attractive in appearance and which may be manufactured at low cost.

All of the foregoing and still further objects and advantages will become apparent from a study of the following specification, taken in connection with the accompanying drawings wherein like characters of reference designate corresponding parts throughout the several views, and wherein:

Figure 1 is a top plan view of an embodiment of the invention.

Figure 2 is a front elevation thereof.

Figure 3 is a vertical longitudinal sectional view, taken substantially on the line 3—3 of Fig. 1, the lower portions of the legs being broken away.

Figure 4 is a view in end elevation of the invention with the seat omitted.

Figure 5 is a view in front elevation thereof.

Figure 6 is a vertical sectional view through an upper portion of the device, taken substantially on the line 6—6 of Fig. 5.

Figure 7 is a vertical sectional view, taken substantially on the line 7—7 of Fig. 6 but showing the seat supporting blocks in raised or operative position.

Figure 8 is a bottom plan view of the removable seat.

Figure 9 is a bottom plan view of a corner portion of the removable seat, showing the slidably mounted adjusting members in operative position.

Figure 10 is a vertical sectional view through an end portion of the seat, taken substantially on the line 10—10 of Fig. 9.

Referring now to the drawings in detail, it will be seen that the embodiment of the invention which has been illustrated comprises what may be referred to as a supporting unit or structure of suitable material, preferably wood, which is designated generally by the reference numeral 1.

The supporting structure 1 includes legs 2 between which a plurality of braces 3 extend.

The reference numeral 5 designates blocks of suitable material which are hingedly mounted on the upper end portions of the legs 2, as at 6. As illustrated to advantage in Fig. 7, of the drawings, the blocks 5 are adapted to be swung upwardly on the upper ends of the legs 2 in a manner to constitute vertical extensions on said legs. The blocks on the front and rear legs 2 are connected by rods 7 for operation in unison.

Removably mounted on the supporting structure 1 is a substantially rectangular seat which is designated generally by the reference numeral 8. The seat 8, it will be observed, comprises a frame 9, a top 10 and an apron 11. Mounted for sliding movement beneath the longitudinal members of the frame 9 are substantially U-shaped members 12. The leg portions of the substantially U-shaped slideable members 12 have formed therein slots 13 which accommodate headed elements 14 for mounting said members 12 beneath the frame 9.

The construction and arrangement is such that four vertical adjustments of the removable seat 8 may be made. The lowest adjustment is shown to advantage in Fig. 3 of the drawings wherein the frame 9 of the seat 8 is resting directly on the upper ends of the legs 2, the blocks 5 and the members 12 being in inoperative position. The next adjustment is made by sliding the members 12 outwardly from the position shown in Fig. 8 of the drawings to that illustrated in Fig. 9, thus permitting the end portions of said members 12 to rest on the upper ends of the legs 2.

Of course, to make these adjustments the seat 8 is removed from the supporting structure 1. The next adjustment of the seat 8 is accomplished by retracting the members 12 and swinging the blocks 5 upwardly to operative position on the upper ends of the legs 2, as shown in Fig. 7 of the drawings. The seat 8, when replaced, rests on the blocks 5. Then, the last and highest adjustment is made by sliding the members 12 outwardly for engagement on the blocks 5.

It is believed that the many advantages of an adjustable piano bench constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:—

1. A piano bench comprising a plurality of legs, a seat removably mounted on said legs, and members slidably mounted on the seat and engageable with the upper ends of the legs for supporting said seat in elevated position thereon.
2. A piano bench comprising, in combination, a plurality of legs, a removable seat adapted to be mounted on said legs, blocks hingedly mounted on the legs and engageable with the upper ends thereof for elevating the seat, and members slidably mounted beneath said seat and engageable with the blocks for supporting the seat in elevated position on said blocks.
3. A piano bench comprising a plurality of legs, a seat adapted to be removably mounted on said legs, said seat including a frame, a top mounted on said frame and an apron depending from the frame, and a pair of substantially U-shaped members slidably mounted beneath the frame and engageable on the upper ends of the legs for supporting the seat in elevated position thereon.

4. A piano bench of the class described comprising a supporting structure including a plurality of legs, braces extending between said legs, a seat adapted to be removably mounted on the legs, said seat including a frame, a top on said frame and an apron depending from the frame, blocks hingedly mounted on the upper portions of the legs and engageable on the upper ends thereof for supporting the seat in elevated position thereon, rods connecting certain of the blocks for operation in unison, substantially U-shaped members slidably mounted beneath the frame and engageable selectively with the blocks or with the legs for supporting the seat in elevated position thereon, the leg portions of said substantially U-shaped members having slots therein, and headed elements mounted in the frame and passing through the slots for slidably securing said members to said frame.

GEORGE W. SMITH.
